(57) **CLAIM**

The ornamental design for a bottle sleeve, as shown and described.

DESCRIPTION

FIG. 1 is a perspective view of a bottle sleeve; FIG. 2 is a front side elevational view thereof; FIG. 3 is a rear side elevational view thereof; FIG. 4 is a left elevational view thereof; FIG. 5 is a right elevational view thereof; FIG. 6 is a top side elevational view thereof; FIG. 7 is a bottom side elevational view thereof; FIG. 8 is an environmental perspective view thereof in an in-use configuration; FIG. 9 is an environmental front side elevational view thereof in an in-use configuration; FIG. 10 is an environmental rear side elevational view thereof in an in-use configuration; FIG. 11 is an environmental left elevational view thereof in an in-use configuration; FIG. 12 is an environmental right elevational view thereof in an in-use configuration; FIG. 13 is an environmental top side elevational view thereof in an in-use configuration; and, FIG. 14 is an environmental bottom side elevational view thereof in an in-use configuration.

In FIGS. 1-6 and 8-13, dotted lines depict stitching along the elastic rim of a front pouch and connecting fabric portions along the sides a rear zippered pocket. In FIG. 1, broken lines are used to depict grip elements which are disclaimed from and form no part of the claimed design. In FIGS. 3, 4, 6, 7, 10-12, and 14, broken lines are used to depict a rear tag which is disclaimed from and form no part of the claimed design. In FIGS. 2, 3, 5-7, 9, and 12-14, broken lines are used to depict a loop and clip which are disclaimed from and form no part of the claimed design. In FIGS. 8-14, broken

(Continued)

lines are used to depict a bottle for the purpose of illustrating a possible environment. The bottle forms no part of the claimed design.
